UNITED STATES PATENT OFFICE

JAMES THOMPSON WILSON, OF NEW YORK, N. Y.

CONSTRUCTION OF CONCRETE AQUEDUCTS, TUNNELS, SUBWAYS, AND THE LIKE.

No. 866,833.

Specification of Letters Patent.

Patented Sept. 24, 1907.

Application filed February 18, 1907. Serial No. 357,802.

To all whom it may concern:

Be it known that I, JAMES THOMPSON WILSON, a citizen of the United States, and residing at New York, in the county of New York and State of New York, have 5 invented certain new and useful Improvements in the Construction of Concrete Aqueducts, Tunnels, Subways, and the Like, of which the following is a specification, such as will enable those skilled in the art to which it appertains to make and use the same.

10 This invention relates to the construction of concrete aqueducts, tunnels, subways, culverts and the like and involves an improved method of making such structures as well as the means employed therein.

The invention pertains particularly to the method 15 of forming concrete walls for the bottom, sides and top of a tunnel, aqueduct or other structure, and in practice an inner core or framework is employed, provided at the sides and top with an inner shell or casing composed of boards or other suitable material, and an outer 20 shell or casing is also employed at the sides and top of the aqueduct, tunnel or other structure, and composed of boards or other material suitably supported, and between the outer and inner shells or casings are placed molds which may be moved forwardly from time to 25 time between said outer and inner shells or casings, said outer and inner shells or casings forming a chamber, the cross sectional form of which is the shape of the sides and top of the aqueduct, tunnel, subway or other structure in cross section, and the dimensions of which 30 is equal to the dimensions or thickness of the side and top walls of the aqueduct, tunnel, subway or other structure, which are composed of concrete, and which are molded between the outer and inner shells or casings as the work progresses, the bottom wall of the aqueduct, 35 tunnel, subway or other structure being also formed of concrete, and the bottom, side and top walls of the said structure being carried forwardly as the construction progresses and being formed of separate sections or subdivisions connected by interlocking joints of different 40 or various forms molded in such manner as to form a continuous homogeneous wall or structure of concrete which will be impervious and through which water or other liquids cannot pass.

In practice, the side molds which are placed between 45 the inner and outer shells or casings in forming the side and top walls of the aqueduct, tunnel, subway or other structure are so formed as to be placed in an inclined position, and the separate sections or divisions of the side and top walls of the aqueduct, tunnel or other 50 structure are connected by inclined and horizontal joints as well as by means of tongues and grooves formed by the molds employed, and this feature of the construction adds to the strength of the sides and top walls of concrete and aids in making such walls impervious 55 or impermeable by water or other liquids.

The invention is fully disclosed in the following specification, of which the accompanying drawing forms a part, in which the separate parts of my improvement are designated by suitable reference characters in each of the views, and in which:

Figure 1 is an end view of the bottom, side and top walls of an aqueduct, tunnel or similar structure made according to my invention and showing the inner and outer shells or casings between which the side and top walls are cast or formed; Fig. 2 a side view of the construction shown in Fig. 1 and showing the outer shell or casing partially broken away, and showing an abutment wall in section against which the structure of the aqueduct or tunnel walls is begun and showing also the molds employed between the inner and outer shells or casings between which the side and top walls of the aqueduct, tunnel or other structure are formed; Fig. 3 a view similar to Fig. 2 but showing the outer shell or casing entirely removed, and showing a part of one side wall of the aqueduct, tunnel or other structure, and 65 showing the molds employed between the inner and outer shells or casings set forward as when beginning a new section or division of the construction of the side and top walls of the structure; Fig. 4 a transverse section through one of the side molds on the lines 4—4 of 70 Fig. 6; Fig. 5 a section through one of the molds on the lines 5—5 of Fig. 3 and Fig. 6; Fig. 6 a side view of one of the corner molds employed at the bottom of each side wall of the aqueduct, tunnel or other structure and by means of which the joints between the bottom and 75 side walls are formed and showing also a part of one side wall mold and a part of the main bottom wall mold; Fig. 7 a plan view of the construction as shown in Fig. 2 with the molds removed and the outer and inner shells or casings removed and showing the main central part 80 of the bottom wall of the aqueduct, tunnel or other structure extended; Fig. 8 a section on the line 8—8 of Fig. 2, and showing the mold partially separated from the concrete side wall, and showing reinforcing rods or bars used in the concrete side wall; and, Fig. 9 a section 85 on the line 9—9 of Fig. 6 and showing a bottom mold separate from a part of the concrete of the bottom wall of the aqueduct or other structure and showing also reinforcing rods or bars used in the concrete of the bottom wall.

In beginning the formation of concrete walls for an aqueduct, tunnel or other structure according to my invention, I preferably provide an abutment wall a as shown in Figs. 2 and 3. I also provide an inner shell or casing a^2 composed of boards or any other suitable 105 material and which, in practice, is supported by a core or framework arranged in the aqueduct, tunnel or other structure together with an outer casing or shell a^3 composed of boards or other suitable material and supported in any desired manner, and between which 110

the concrete side and top walls *b* of the aqueduct, tunnel or other structure are formed, and I also provide side molds *c* and a top mold *d* which are adapted to be placed between the outer and inner shells or casings *a*² and *a*³, and in the form of construction shown, four of the side molds *c* are employed on each side, and in connection therewith are employed combination corner molds *e* which serve to form the bottom parts of the concrete side walls of the tunnel or aqueduct, and the adjacent side portions of the bottom wall *b*², and in connection therewith I also provide a main bottom mold *f* indicated in Fig. 1 and partially shown in Fig. 6.

The top mold *d* is angular in form and composed of 15 horizontal side bottom portions *d*² and a transverse vertical portion *d*³, and the side molds *c* are angular in form as clearly shown in Figs. 2 and 3 being composed of a horizontal bottom portion *c*² and an upwardly and 20 backwardly inclined portion *c*³, and these side molds when placed together between the side portions of the shells or casings *a*² and *a*³ range upwardly and backwardly or in the direction of the abutment wall *a*. The rear faces of all of the molds *c*, *d*, *e* and *f*, or the 25 faces thereof which are directed toward the abutment wall *a*, and the bottom faces of the side portions *d*² of the top mold *d* and the bottom faces of the bottom parts *c*² of the side mold *c* are provided with tongues and grooves. A cross section of the upper inclined part 30 of one of the molds *c* is shown in Fig. 4, said section being taken on the dotted lines 4—4 of Figs. 3 and 6, and a cross section of the angular or bottom portion of one of the molds *c* is shown in Fig. 5 said section being taken on the line 5—5 of Fig. 3, and this part of the mold *c* is the same in cross section as the bottom part of the 35 angular corner molds *e* employed at the bottom corners of the side wall construction and where said corners join the bottom wall of the aqueduct, tunnel or other structure.

The tongues and grooves in the faces of all the molds 40 *c*, *d*, and *f* are preferably substantially similar and consist of a main projecting central tongue *g* at each side of which are smaller tongues *g*² forming corresponding grooves *g*³, and the tongues *g*² on one side of the central tongues *g* are preferably of a shape in cross section 45 different from those on the other side. The central tongues *g* of the upwardly and backwardly inclined portions of the molds *c* and *e* are preferably what are called locking tongues, the outer transverse dimensions thereof being greater than the inner transverse dimensions, and these tongues are removable when the molds 50 are in position and passed downwardly through the bottom horizontal portions *c*² of each of the molds *c* into the upper and backwardly inclined portion of the next mold thereunder, while the tongues *g* of the horizontal bottom portions of the molds *c* and of the mold *f* 55 are of the same transverse thickness throughout and are not made removable.

In Fig. 8, I have shown a section on the line 8—8 of Fig. 2, in which one of the molds *c* is shown and a part 60 of one of the side walls *b* of the aqueduct, tunnel or other structure together with reinforcing rods *h* which may be employed, if desired, but which are not an essential feature of my invention, and in Fig. 9, I have shown a section on the line 9—9 of Fig. 6 in which a 65 part of the bottom mold *f* is shown together with a

part of the bottom wall *b*² of the aqueduct, tunnel or other structure.

In practice, the corner molds *e* and bottom mold *f* are first placed in position at a predetermined distance from the abutting wall *a* and the material of the bottom wall *b*² of the aqueduct, tunnel or other structure is placed in position so as to fill the space between the mold *f*, the molds *e* and the abutting wall *a*. The central frame or core work which supports the inner shells or casings *a*² is placed on this part of the bottom wall 70 *b*² after the material thereof has hardened and projected forwardly, and the inner casing or shell *a*² is placed in position thereon, and the outer casing or shell *a*³ is also placed in position, after which the side and top molds *c* and *d* are placed in position between the 75 shells or casings *a*² so as to correspond with the position of the corner molds *e*, and the space between the molds *e* and *d* and the abutting wall *a* is then filled in with concrete. This forms the first section of the side, top and bottom concrete walls of the aqueduct, tunnel 80 or other structure, and after the concrete has partially set, the locking tongues *g* are drawn out of the molds *c* and *e* and the bottom mold *f*, corner molds *e* and side and top molds *c* and *d* are moved forward a predetermined distance, the locking tongues *g*⁴ of the molds *c* 85 and *e* are placed in position and another section or division of the concrete bottom side and top walls is packed in between the molds and the last previous section or division of said concrete bottom side and top walls. When the bottom, corner, side and top 90 molds *f*, *e*, *c* and *d* are moved forward the various tongues and grooves in the faces thereof leave corresponding grooves and tongues in the corresponding face of the bottom side and concrete walls of the aqueduct, tunnel or other structure, and when the following division or section is placed in position the grooves in the preceding section or division which has become 95 hard are filled in with concrete and the tongues of the preceding section extend into the new section or division of concrete and in this way the separate sections 100 or divisions of concrete are completely locked together, and continuous walls are formed.

In practice, I prefer to extend the bottom wall *b*² of the aqueduct, tunnel or other structure forward as shown at *b*³ in Fig. 7 so as to form a support for the central core or frame with which the inner shell or casing *a*² is connected, and in this case the bottom mold *f* may or may not be employed, or the entire bottom portion of the floor of the aqueduct, tunnel or other structure may be so carried forward together with the bottom portion 110 of the side walls thereof, in which event, both the central bottom mold *f* and the corner molds *e* may be employed as hereinbefore described, and in carrying forward the side and top walls the molds *c* and *d* will also be employed as hereinbefore described; it being 115 understood that, in practice, all of said molds are carried forward a predetermined distance at each operation, after which the concrete forming the walls of the structure is filled in between the shells or casings *a*² and *a*³ and this operation is repeated until the walls of 120 the aqueduct, tunnel or other structure is completed and any suitable means may be provided for gaging the thickness of the bottom wall *b*² and for giving it the required shape in cross section.

My invention is not limited to the particular form 130

- of the molds shown and described nor to the particular form of the tongues or grooves with which the faces thereof are provided and any molds of any preferred construction which may be operated in the manner 5 herein shown and described and which will provide in each section or division of the completed wall grooves and tongues which will interlock with other tongues and grooves in the next succeeding section or division will answer all necessary requirements, it 10 being understood that the side molds should be so formed as to make an inclined joint for the succeeding sections or divisions as indicated in Figs. 2, 4 and 7.
- The use of an abutment *a* at the beginning of the aqueduct, tunnel or other structure is not absolutely 15 necessary and for this purpose the molds *c*, *d*, *e* and *f* may be employed, in which event, the position thereof will be reversed, or two sets of such molds may be employed for beginning the construction of the walls of the aqueduct, tunnel or other structure.
- 20 It will be understood, of course, that the shells or casings *a*² and *a*³ form together a complete casing in which the side and top walls of the tunnel, aqueduct or other structure are cast or formed, and these inner and outer shells or casings *a*² and *a*³ may be constructed and supported in any desired manner.

It will be observed that the bottom of the inner shell or casing *a*² is higher than the bottom of the outer shell or casing *a*³, the distance between the bottom portions of said shells or casings determining the thickness of the 30 bottom wall of the aqueduct, tunnel or other structure, and this affords means for the proper joining and connection of the bottom wall with the side walls of the aqueduct, tunnel or other structure.

Having fully described my invention, what I claim 35 as new and desire to secure by Letters Patent, is:—

1. The method herein described of forming the walls of an aqueduct, tunnel or other structure which consists in providing a casing for the side and top walls, side and top molds adapted to fit in said casing and to be moved longitudinally thereof, a bottom mold operating in connection with the side molds and adapted to be moved therewith, and moving said molds forwardly step by step and filling in the spaces thus formed in said casing with concrete to form the side and top walls and filling in the bottom portion 40 with concrete to form the bottom wall.
2. The method herein described of forming the walls of an aqueduct, tunnel or other structure consisting in providing a casing for the side and top walls at the bottom of which is a space for the bottom wall, an abutment against 45 which said casing is placed, side and top molds which are adapted to fit in said casing, and bottom molds operating in connection with the side molds, and moving said molds forwardly step by step and filling in the casing with concrete rearwardly of said molds at each successive forward movement of said molds and also filling in the bottom of 50

the aqueduct, tunnel or other structure with concrete to form the bottom wall.

3. The herein described means for forming the side, top and bottom walls of an aqueduct, tunnel or other structure of concrete, comprising inner and outer sides and top 60 shells or casings, separate side and top molds adapted to be placed in the space between said shells or casings and to be interlocked, and a bottom mold adapted to operate in connection with the side molds, said molds being provided in their faces with grooves and ribs to form corresponding 65 ribs and grooves in the concrete, and said molds being also adapted to be moved forwardly step by step.

4. The herein described means for forming concrete walls for an aqueduct, tunnel or other structure, comprising inner and outer shells between which the side and top 70 walls are formed, the inner shell being higher at the bottom than the outer shell, side and top molds movable between said shells, and a bottom mold operating in connection with the side molds and adapted to be moved there- 75 with forwardly step by step.

5. The herein described means for forming concrete walls for an aqueduct, tunnel or other structure, comprising inner and outer shells between which the side and top walls are formed, the inner shell being higher at the 80 bottom than the outer shell, side and top molds movable between said shells, and a bottom mold operating in connection with side molds and adapted to be moved therewith forwardly step by step, the faces of said molds being provided with tongues and grooves which extend longitudinally thereof.

6. The herein described means for forming concrete walls for an aqueduct, tunnel or other structure, comprising inner and outer shells between which the side and top walls are formed, the inner shell being higher at the 85 bottom than the outer shell, side and top molds movable between said shells, and a bottom mold operating in connection with side molds and adapted to be moved therewith forwardly step by step, the faces of said molds being provided with tongues and grooves which extend longitudinally thereof, and the side molds being composed of 90 horizontal bottom portions and upwardly and backwardly inclined top portions.

7. The herein described means for forming concrete walls for an aqueduct, tunnel or other structure, comprising inner and outer shells between which the side and top walls are formed, the inner shell being higher at the 95 bottom than the outer shell, side and top molds movable between said shells, and a bottom mold operating in connection with side molds and adapted to be moved therewith forwardly step by step, the faces of said molds 100 being provided with tongues and grooves which extend longitudinally thereof, and the side molds being composed of horizontal bottom portions and upwardly and backwardly inclined top portions, and means for locking the side molds together and for forming locking grooves in 105 the concrete.

In testimony that I claim the foregoing as my invention I have signed my name in presence of the subscribing witnesses this 15th day of February 1907.

JAMES THOMPSON WILSON.
